UNITED STATES PATENT OFFICE.

FRANK J. ROSENBERG, OF LOS ANGELES, CALIFORNIA.

DESIGN FOR A TOY.

No. 40,173.

Specification for Design.

Patented July 27, 1909.

Application filed March 17, 1909. Serial No. 484,330. Term of patent 3½ years.

To all whom it may concern:

Be it known that I, FRANK J. ROSENBERG, a citizen of the United States, residing in the city of Los Angeles, in the county of Los Angeles, in the State of California, have invented a new, original, and ornamental Design for Toys, of which the following is a specification, reference being had to the accompanying drawing, forming part thereof.

The figure is a perspective view showing the design of the toy.

I claim:

The ornamental design for a toy, as shown.

FRANK J. ROSENBERG.

Witnesses:

ST. JOHN DAY,

IDA M. DASKAM.
